UNITED STATES PATENT OFFICE.

ARTHUR H. ADAMS, OF LAKEVILLE, CONNECTICUT.

INDOOR GOLF GAME.

Application filed January 6, 1922. Serial No. 527,375.

To all whom it may concern:

Be it known that I, ARTHUR H. ADAMS, a citizen of the United States, and residing at Sharon Road, Lakeville, Connecticut, have invented certain new and useful Improvements in Indoor Golf Games, of which the following is a specification.

This invention relates to an improvement in indoor golf games, and particularly to an improvement in such games playable on a table or other restricted space and involving skill of an order not unlike that required for ordinary golf.

The objects of this invention are to provide, particularly for golfing enthusiasts and for those who would learn the rules, the language and some of the important elements of skill of outdoor golf, a wholesome relaxation together with an opportunity to employ or obtain the knowledge of said rules, language and elements. Another object is to produce such a game in which practically all of the varied conditions of golf are reproduced in miniature; in which by allowing an infinite variety of golf 'holes' to be combined by the players the tedium of ordinary games of this class is eliminated and the rudiments of golf-course architecture are taught; in which the tremendous variety of strokes or 'shots' of the parent game are faithfully duplicated, together with the main varieties of different clubs, in which the ball may be rolled, 'topped', 'lofted' more, or less, given practically all of the various impulses the ball receives in the parent game, and specially in which the ball is readily driven through the air over obstructions or 'hazards'. A further object has been to design the game almost exactly 'to scale'. In this I believe it is unique. By this term 'to scale' I mean among other things, and chiefly, that the distances to which the ball in my invention can be by the ordinary player be propelled bear quite closely the same relation to the length of the various 'holes', i. e., of the courses from 'tee' to 'cup', as the corresponding 'shots' would bear to corresponding 'holes' in outdoor golf.

Before further describing these features and the method of accomplishing them, the accompanying drawing should be referred to.

Fig. 1 is a plan, and Fig. 2 a section on

line AA of Fig. 1, of the preferred form of 55 playing course, with some of the movable hazards and other features dotted in in plan and in elevation to show a typical arrangement or 'hole.' This playing course, it will be seen, comprises a shallow long tray with the 60 bottom covered with a fuzzy fabric, like billiard cloth or Canton flannel. The tray hinges at the middle and closes up to a very compact and portable form as shown in Fig. 3. As stated below in this specification 65 the approximate dimensions that have been elaborated give a tray of about 5 feet long by one and one-half feet wide when opened out. The movable elements shown dotted in 70 the plan, Fig. 1, and which will be more particularly described below are from right to left the 'tee', a piece of 'rough', the side incline, the 'water hazard', two large 'bunkers', a hill, the 'green', and two 75 small 'bunkers' flanking it.

It should be understood that the tray or specially provided playing surface is not an essential element of this invention. This game could be, and has been, played with entire satisfaction on a felt table cover or the 80 like with the tee, green and various hazards arranged upon it.

Fig. 4 shows a section across the tray on the line BB of Fig. 1. Like the other section it shows in dotted elevation certain of 85 the movable elements—the 'green', a small 'bunker', a conical bunker called a 'chocolate drop' and a side incline.

Fig. 5 shows a perspective of the three pieces of side incline provided. The purpose is described below. The first two at the left are cut off each at one end at an angle of 45 degrees so that they will fit together and form a mitre in the corner of the tray in case it seems desirable to provide the incline 90 at the end as well as the side. These pieces are not covered with fabric, and are very smooth or polished on the upper or slanting surface. See the left hand dotted element of 95 Fig. 4 for a better understanding of the cross section and the use of these inclines than the perspective gives.

Fig. 6 shows a plan, and Fig. 7 a section on line CC of Fig. 6, of a movable conical 'bunker' or obstruction called a 'chocolate 100 drop'. This is one of the common forms of 'bunkers' on golf courses. It is covered with a fabric having a nap.

Fig. 8 shows a plan of the movable 'green' or 'putting green.' Fig. 9 shows a section on line DD of Fig. 8. It has a thickness at least equal to half the diameter of the ball. It is preferably moulded of a cheap green rubber or rubberoid composition, without too much elasticity but sufficiently heavy and flexible to hug the larger irregularities of a surface on which it may be laid. It has been found that a stiffer material, due to its own 'life' and to slight varying of the tray, etc., will not always lie steadily without rocking and with the sharp edges down all around on the bottom of the tray. A hole termed the 'cup' is cut clear through the 'green.' This is the goal into which the ball is to be struck in the fewest possible strokes from the 'tee.' The miniature flag, with its supporting lead or other heavy base, is not an essential in this small sized game. It is added to give verisimilitude. In the outdoor game it is essential that the player have some indicator of the position of the 'cup' which at a distance of several hundred yards would be invisible.

Fig. 10 and Fig. 12 show respectively plans of the larger and smaller straight 'bunkers,' two of each being preferably provided with the game, though the number and different sizes are not essential. Fig. 11 and Fig. 13 show sections on the lines EE and FF respectively of Figs. 10 and 12. These 'bunkers' also are preferably covered with a nap to simulate grass and impede ricochetting of the ball.

Fig. 14 is a plan, Fig. 15 a section, on line GG of Fig. 14, of the movable 'tee' or 'teeing ground.' This is the raised mound from which the players initially strike the balls in the direction of the 'green' and its 'cup.' The circular raised spots are markers: The ball must be struck from behind and between these markers.

Figs. 16 and 17 are plan and elevation respectively, of a movable piece of 'rough.' This is a piece of very long-napped green fabric, to simulate tall grass or weeds on a regular golf course. Figs. 18 and 19 show a very similar piece of fabric except that the outline is chosen to represent a pool or enlargement in a water course, and the color of the fabric is light blue or bluish gray to simulate or suggest water. This is termed the 'water hazard.' The long nap has a tendency to hold the light fuzzy ball to be described below and the player whose ball lodges therein is forced by rule to repeat his stroke just as if in the outdoor game his ball had fallen in a pond. The 'water hazard' is of course movable.

Fig. 20 is an enlarged view of the ball preferably used, which is coated with short wool fuzz such that it is impeded in rolling on the main felt playing surface of the tray —termed the 'fairway'—and is practically

prevented from rolling at all in the 'rough' and the 'water hazard.' This coating also slows down its flight in air.

Fig. 21 shows a section of the preferred ball structure, being an extremely light gelatin or celluloid shell, coated with the fuzz as described. Before the clubs are described it should be stated that the exact form and number of the 'hazards' of various sorts are a matter of taste. A representative and preferred collection is shown. No separate detailed view is given of the largest hazard shown in Figs. 1 and 2; namely the hill. This is merely a movable elevation with more or less sloping sides—here indicated as practically a low pyramid—and covered with a nap. The top is indicated of a size equal to accommodating the green if it be desired to combine a very difficult 'hole.' Strips of light brownish fabric with a long nap like that of the 'rough' and of the 'water hazard' may be provided, and termed 'pits' or 'sand traps.' 'Sand traps' are commonly placed in front of 'bunkers' on outdoor courses, and make the act of playing the ball over the bunker more difficult. Similarly small bits of rough matting appropriately colored could be provided to suggest, and to fulfil the aggravating function of, brush or bushes. An uphill or downhill course is provided by propping up from the table on which it rests one end or the other of the tray. In that case the slight opening at the center would be covered by the piece of 'rough,' by 'bunkers' or by the hill, etc.

The 'clubs' or playing implements proper are shown substantially natural size in Figs. 22 to 25. They are in this order, 'putter,' 'driving iron,' 'mashie,' 'niblick.' More varieties could as well be provided, but the player can so readily adjust these clubs that greater refinements seem unjustified. These implements are constructed of spring wire having a short tight coil at one end of a diameter to grip the stem provided, see below, and having an offset anchorage loop at the other (not shown) around which the 'head' of Babbitt or white metal is cast in a mould or die. The different angles and shapes of these 'heads' will be familiar to the golfer, although it should be stated that, excepting the putter, more 'loft,' i. e., tendency to lift the ball, has been found advisable on these small clubs than on their full size corresponding prototypes.

Fig. 26 shows the 'driving iron' on its stem or handle in two of an infinitude of possible adjustments. In the full lines an average or normal adjustment is shown, with the striking end or 'head' of the club substantially flat to the ground and the stem somewhat over 45 degrees from the horizontal. By sliding the coil, which makes

a simple and very effective friction adjustment, farther up the stem and leaning the stem nearer to the ground a more vertical stem nearer to the ground a more vertical swing is obtained. The 'shaft' or wire joining the club 'head' and the coil may also be bent a little nearer the coil by the player to suit his whim. In this connection should it be necessary to play the ball from the top of a 'bunker' where the point of 5 the stem could not be steadied on the same level as the ball the coil friction may be slid way up the stem toward the finger grip and the stem thus lengthened may be stood on the ground well below the level the ball 10 is on. Or, if the ball is in a depression between bunkers or the like, the stem may be shortened by the reverse process and stood upon a surface well above the ball. This is frequently convenient when the ball lies at 15 the foot of the side incline. It is even best 20 at times to pivot the stem on the vertical sides of the rim of the tray, or on the very steep side of a 'bunker'.

Fig. 27 is a view like Fig. 26 except that 25 the club shown is the 'niblick' and this view shows the special small finger hold or handle of the stem intended for use with this club. This club is short and 'lofted' or 'laid back' very much, i. e., the striking 30 face of the head approaches the horizontal. For this reason, and to enable the ball to be struck upwards over a 'bunker' or obstruction close in front, a sharper blow is found necessary than for the other clubs. This 35 the smaller handle allows.

The foot P of the stem has a needle point 40 springing from a slight shoulder in a long bevelled point; this enables it to hold at almost any angle like a drafting instrument but without undue penetration.

It will be obvious from the above consideration of the drawing that this game reproduces in miniature and reasonably true to scale the main or standard features encountered on any golf course. The drawing does not show for obvious reasons the instruction booklet that is intended to go with the game. Herein may be given the vocabulary of the game, which is that of the parent game, the rules which may be practically without modification the current rules of the United States Golf Association, and a series of charts for building or combining different typical 'holes,' and others in quite close fac-simile of 'holes' of famous links. It is thus seen how the invention easily attains a number of the recited objects. But it is not easily seen on the drawing how the invention really reproduces most conditions of real golf; the various and difficult 'lies,' i. e., chance positions of a ball more or less readily playable; the 'hazards' or obstructions with their moral effect on the player; the enticement to over-exert and fail of accuracy that is summed up by the golfer in

the word 'pressing'; the variety of ways in which a player may take his 'stance' and 'address' the ball; the variety of characteristic impulses that may be given a ball causing it to rise higher or less high over obstructions and stop where desired without chance rolling, causing it to sail forward for distance, or to roll accurately on the 'putting green.' To solve these problems a tremendous amount of experiment was done, 70 and it became clear that if a ball and a club could be designed that would cooperate to make it possible to drive a ball in a trajectory through the air and yet practically impossible to drive it an excessive distance 75 in relation to the size of the playing ground provided, then a majority of the wanted resemblances to outdoor golf would be present. This is the most important single feature 80 of this invention, that the 'shots' are to 85 scale with the 'links,' and, of course, that they are real 'shots,' having nearly as much variety of trajectory as is obtained, and having in their execution a close approach to 90 the difficulty found, in the parent game. 90

It became clear that an exceedingly light ball for its size would be necessary. The blow necessary to cause a heavy ball to soar would inevitably impart to it such momentum or energy that it would travel much farther than 'to scale' with any practicable miniature playing ground or 'hole'. The lightest practicable ball was thus chosen, and the drawing shows a thin walled hollow sphere. This is preferably made of a gelatine composition similar to that used for medicine capsules, but chemically treated for greater resistance to moisture. However, celluloid, or other cellulose material, even 95 glass or metal if thin enough, in fact any 100 stiff material that can be formed into an exceedingly light sphere would be satisfactory. Or it would not depart from the true spirit of this invention if a solid ball sufficiently light were commercially practicable. 105 Pith balls are excellent when carefully shaped round. A ball of very light fluffy wool felt, or a ball rolled up of lamb's wool is also good. The materials mentioned have 110 all been tried, and many others. The hollow gelatine ball is preferred merely for cheapness, although it should be stated that the lightest obtainable hollow glass and metal spheres are heavier than the others. 115

Further to shorten the trajectory of the ball due to a given impulse the highest coefficient of friction in air was sought. Nothing was found equal to a coating of 120 lint or fuzz such as imparts to a new tennis ball its remarkable curving properties. A woolen lint coating on the ball is the preferred form. Any roughnesses are of assistance, and the use of a sand-blasted or crinkled, or otherwise roughened ball for the 125 purposes and in the manner of this invention 130

tion would not depart from the spirit thereof.

It was further found that the fuzzy coating of the ball gave it an action on a fuzzy playing ground very like a golf ball in the grass of a properly conditioned links, in that the tendency to roll was checked and the proportion of the roll to the trajectory kept approximately the same as of a golf ball in such grass. The preferred ball on a slick surface like a table naturally rolls disproportionately and the whole length of its travel is too great. Clearly this short-rolling effect could be approximated by the use of many different treatments of the surface of the miniature playing ground or 'fairway'. A 'fairway' covered with a fuzzy fabric like billiard cloth or Canton flannel, naturally dyed to resemble the green of a real course, is my preferred form. The yielding nature of this surface also simulates real turf to the action of the club heads, and is an advantage. A wooden or paper surface coated with an adhesive and lint, or even with an abrasive or a surface in any-way roughened to cling to the ball could be used without departing from this invention.

In order to simulate the more accurate rolling of a golf ball on the special grass of a 'putting green' a relatively hairless and non-clinging surface is provided for the miniature 'putting-green'. A green-colored heavy flexible and 'soggy' composition, like the cheaper grades of rubber used as a floor covering, because it will conform to very considerable irregularities of the surface beneath, is the preferred surface for the miniature 'putting green'. Wood, leather, paper, fibre, metal, painted or bare naturally could be used within this invention. Roughnesses if not sharp and adapted to cling to the ball are not objectionable, such as the grain of some leathers or leather imitations. The term 'slick' is used in this specification to define absence of minute and sharp roughnesses, a sort of microscopic smoothness, the term 'smooth' being of too broad an application.

An extremely clinging surface was desired to simulate the real 'water hazard'. A driven ball in real golf occasionally skips or ricochets over the surface of water, but usually is held by the water and is unplayable. A very fuzzy wool felt of suitable light blue color is the preferred material for the miniature water course, which it is seen is capable of being shifted in the miniature landscape. The ball of this invention will occasionally, but rarely, roll off from this surface, and the possibility of loss of a stroke faces the player making a shot across this miniature 'water hazard', with practically the same effect as in the outdoor game of causing him to be overcautious, panicky or more than usually steady according to his

temperament. The choice of wool felt for the 'water hazard' and of woolen lint for the coating of the ball depends upon those properties of woolen fibres that make felt possible, namely that the fibres are covered with microscopic hooks or scales that grip other fibres, that they are kinky and therefore more readily entangled, and also upon the fact that wool fibres are very elastic. The last remark applies only to the coating of the ball.

The movable 'bunkers' and 'rough' and the movable hill and 'teeing ground' are sufficiently explained by the drawings and the description above, but before leaving the subject of the nature of the surfaces and materials found best adapted to co-operate with the ball the object of the ball-returning inclines Fig. 5 should be more fully explained.

According to the rules of golf a ball within the bounds of the course must be played as it lies with certain exceptions. Even in these exceptions permission to move the ball is usually accompanied by a penalty. It is obvious that when in this game a ball comes to rest next to the left-hand rim of the box or tray in which it is played the clubs provided cannot be used to strike it except in the wrong direction, back toward the 'tee' or starting point. In order to avoid either a special rule, or a special club played oppositely to the others and therefore unhandy to the player, a smooth and slick incline Fig. 5 is provided that can be fitted next to the rim. A ball will roll off from this to a position where the clubs provided can be brought to bear. If it should stop at the very foot of the incline the pivoting point P Fig. 26 of the club may be rested at some point on the incline and the ball becomes readily playable. These inclines Fig. 5 are made movable in order that they may be used on either side of the tray, or at the ends, depending upon how the 'hole' is laid out in the tray by the players. They might also serve on occasion as 'bunkers'.

It is clear that, light and air resistant as the ball may be, a sufficiently sharp blow would drive it to a distance out of scale to a table game. It might be here stated that the approximate scale of this game, not of course rigidly applied to all dimensions of the parts, but to the main dimensions of the playing grounds and to the length of shots, is one foot to one hundred yards. A blow sufficient to propel the light ball a couple of feet in the air is practically the limit aimed at. This limiting strength of blow is quite closely approximated by the design and proportions of the playing implement or club. The further roll-retarding property of the preferred main playing surface or 'fairway' limits the ordinary player to a length of shot quite in the scale of the

miniature playing course provided. This course is approximately five feet long, or to my scale—a five hundred yard 'hole' as a maximum.

5 It will readily be understood that a different scale might be adopted than that of approximately one foot to one hundred yards without in any way departing from the spirit of this invention. If this were done the 10 three elements, the ball, the course and the club would have to be kept in proper relation or proportion to each other. A longer course would allow either of a more heavily hitting club—the factors determining the 15 blow of the club being described below—or of a heavier ball, or both; also some modifications in the fineness of the surface of the ball and the 'fairway' might be desirable for refinement if the new scale were materially different from that experimentally determined and described. None of these changes would depart from the spirit of this invention.

The design of the club will be seen, by 20 examination of the drawings, to provide a motion for the club head H Fig. 27, practically identical with that of a good golf player, at least for the important part of the swing where the club is approaching and 25 in contact with the ball. This is a substantially circular swing in a plane at an angle to the playing surface—the angle depending upon the club used and the whim of the player—and the circle described being 30 usually practically tangent to the playing surface. In any case it must intersect the ball. The 'chip shot' in which the club head is driven more or less downwards and 35 strikes the turf just under the ball without 'follow through' is an example of a stroke in which the club head does not swing tangent to the ground. This and many other special 'shots' are as possible with the clubs 40 of this invention as in real golf.

45 The length of the shaft S Fig. 27 is a factor in the strength of blow, the speed at which the club handle G, Fig. 27 may be twirled is another and the weight of the club head H, Fig. 27 is a third. It is impossible 50 to describe or to determine accurately the relation of these factors. The relations obtained and shown in the drawings substantially to scale, are the result of much labor, 55 based however on the theory proven correct that the larger the circle described by the club head, the heavier that head and the smaller the handle G, the harder the possible maximum blow. One of the points to note in understanding this invention is that 60 an enlarged handle, substantially cylindrical and cut off square at the end effectively limits the speed with which a player can twirl the club. It will be noted that the handle of the 'niblick', Fig. 27, is smaller 65 than that of the three other clubs shown.

This is because the angle of the striking face of this club is so flat, so much 'laid back' in golf language, that a harder blow is found desirable to insure lifting the ball well over obstructions that lie close ahead. 70

The springy grip or hold of the coiled end of the shaft S on the stem B is a valuable feature of the invention. It enables a player whose ball may lie higher or lower than the foot hold of the point P of his club to 75 adjust the shaft up or down the stem to obtain the proper swing and presentation of the club head to the ball, which he could not obtain by inclining the stem if the shaft were not so adjustable. This feature, and 80 the fact that the spring wire shaft may readily, though not too readily, be bent where it branches from the stem, also twisted, enables the player to adapt his individual clubs to his personal idiosyncrasies. Thus one 85 player in real golf will drive with a very flat swing, i. e., the plane of the path of his club head where it hits the ball will approach the horizontal. Another will drive with a swing approaching the vertical. 90 These idiosyncrasies may be copied with the clubs of this invention by means of the adjustments mentioned.

It will be clear that the coiled wire grip of the shafts, S, on the stems of Fig. 27, or 95 the use of wire for the shafts, or of white metal cast on the wire for the club heads, H, are not essential features. A punched shaft, head and friction grip, all in one piece, could for example be made, or any other 100 suitable construction could be used without departing from the spirit of this invention. Similarly the stem or body could take many forms including its disguise as a miniature player, or the pivot point thereof could be 105 replaced by a suitable swiveled shoe, or many other modifications could be made without departing from this invention.

The position of the pivoting point of the 110 club in relation to the ball must be carefully chosen by the player, it has its effect upon the direction, distance and elevation given to the ball, as also does the inclination of the stem to or from the ball, forward or back. These points, apparently simple, constitute a study when actually playing with this game suggesting at least some of the problems of 'stance' in the parent game.

The inability of a player to hold the stem 115 steady, and thus assure the accurate presentation of club head to ball, when striving to twirl the club violently puts almost the identical premium on self control as the dangers of the similar fault called 'pressing' in real golf.

The terms of the game of golf have been used throughout this specification and the claims in their accepted meaning in that game. They have been put in semi-quotation because they are technical or special 120 125

terms belonging only to one sport, also because some of them without this distinguishing mark might be construed in their more usual sense, as for instance 'hole' which in 5 the game of course signifies the whole playing course from one 'tee' or starting point to the corresponding 'putting green' and 'cup,' i. e., to the corresponding goal, and does not signify the 'cup' or 'hole' into 10 which the ball is finally knocked or 'putted.'

What I claim is:

1. In a miniature golf game, a ball of little mass and of relatively high air resistance, a club, a manually rotatable handle operating said club to strike said ball, and having a diameter tending to limit the kinetic energy imparted to said ball.

2. In a miniature golf game, in combination, a very light ball, a yielding and porous surface on said ball presenting high resistance to rolling and to flight, a minute golf club comprising a shaft and a head, a handle rotatable between the fingers operating said club to propel said ball and having its diameter so proportioned to the length of said shaft as to limit the distance said ball is propelled.

3. In a miniature golf game, in combination, a light fuzzy ball, a club to propel said ball, a twirlable member to operate said club, a manually operable handle on said member of relatively large diameter to limit the speed of twirling, and in cooperation with said ball to limit the distance said ball 35 may be propelled.

4. In a miniature golf game, a light, hollow fuzzy ball, a club to propel said ball, a handle rotatable between the fingers, operating said club and having a diameter limiting the speed of rotation and thereby in cooperation with said ball limiting the distance to which said ball may be propelled.

5. In a miniature golf game, a light lint coated ball having high resistance to passage through air, a club to propel said ball in a trajectory, a handle device to operate said club adapted to be twirled between the player's fingers and having the finger-seized portion of a relatively large diameter to limit the speed of twirling and in cooperation with said ball to limit the trajectory thereof.

6. In a miniature golf game, a 'hole', a raised edge about said 'hole', a fuzzy ball, a slick slope adjacent to said edge to roll said ball away from said edge.

7. In a miniature golf game, a miniature 'hole', a light ball, an implement to propel said ball, an operating means for said implement so proportioned to the player's hand, to said implement and to said light ball as to limit the length of a 'shot' substantially to the scale of said hole.

8. In a miniature golf game, a miniature

'hole', a fuzzy surface on said 'hole', a light fuzzy ball, a miniature golf club comprising a shaft, a hand operated device to swing said club proportioned to the player's hand and to the length of said shaft and cooperating with said fuzzy ball, and said fuzzy surfaces to limit a 'shot' substantially to scale with said 'hole'. 70

9. In a miniature golf game, a miniature 'hole', a light fuzzy ball, a miniature golf club, means to swing the latter comprising a handle to be rotated between thumb and finger, the length of said club, the weight and air resistance of said ball and the diameter of said handle being in such relation 80 that the length of a 'shot' is limited substantially to scale with said 'hole'. 75

10. In a miniature golf game, in combination, a fuzzy playing surface, a light fuzzy ball, a miniature club, means to swing 85 said club comprising a handle of relatively large diameter with respect to the size of said club adapted to be rotated by the thumb and fingers.

11. In a miniature golf game, a tray, a fuzzy ball, a miniature 'hole' in said tray comprising a miniature 'bunker' and 'putting green' and a fuzzy playing surface, a raised edge limiting said tray, and a movable slick ball-returning incline capable of 95 being placed against said raised edge to return said ball inward from said raised edge to a playable position. 90

12. In a miniature golf game, a main fuzzy playing surface, miniature 'hazards' 100 movable on said surface, a miniature slick 'putting green', movable on said surface, cooperating to form a variety of 'holes', a light fuzzy ball, and a set of miniature clubs. 105

13. In a miniature golf game, a main fuzzy 'fairway', miniature 'hazards' movable on said 'fairway' and a miniature 'teeing ground' movable on said 'fairway' 110 cooperating to form a variety of 'holes', a light ball, and a miniature club comprising a twirlable handle of such diameter as to swing said club with a limited velocity.

14. In a miniature golf game, a playing surface, a ball to lie on said surface, a playing implement comprising a body portion with a pointed foot to rest on said playing surface, a handle at the upper end of said body portion, a miniature golf club rigidly branching from said body portion between 115 said foot and said handle. 120

15. In a miniature golf game, a playing surface, a ball to lie on said surface, an implement to propel said ball comprising a body portion supportable at a point on said surface and rotatable by the player's hand about an inclined axis through said point, and a miniature golf club branching from 125 said body portion.

16. In a miniature golf game, a playing 130

surface, a ball to lie on said surface, an implement to propel said ball comprising, rigidly connected, a pivoting end substantially on said surface when in use, a handle end held when in use above said surface, but not directly over said pivoting end, and a miniature golf club head out of the line of the other two and swinging when in use approximately in an arc having said line for an axis and tangent to said playing surface.

17. In a miniature golf game, a playing surface, a ball to lie on said surface, an implement to propel said ball comprising a body portion, a sharp point formed at one end thereof to penetrate slightly into and revolve upon said surface when in use, a generally cylindrical handle at the upper end of said body portion held when in use above said surface but not directly above said point, and a miniature golf club branching from said body portion.

18. In a miniature golf game, a playing implement comprising a stem, a point at one end of said stem, a handle portion above said point, and a miniature golf club branching from said stem.

19. In a miniature golf game, a playing surface, a ball to lie on said surface, a playing implement comprising a stem to be held when in use in a position inclined to said surface and toward said ball, a handle portion to be held by the player to twirl said stem, and a miniature golf club branching from said stem.

20. In a miniature golf game, a stem, a pivoting end on said stem, a shaft branching from said stem and adjustable along said stem to obtain a desired relation between the pivoting end the axis of said stem and the end of said shaft, a miniature golf club head on the end of said shaft.

21. In a miniature golf game, a light ball, a fuzzy exterior surface on said ball, a club to hit said ball, a means comprising a handle of proper diameter rotatable by a player's hand to impart a suitable motion and suitable limited velocity to said club, a miniature 'hole' to a scale substantially in proportion to the distance said ball may be projected by said club and said means, a fuzzy playing surface forming part of said 'hole.'

22. In a miniature golf game, a light ball, a fuzzy exterior surface on said ball, a club to hit said ball, a means comprising a handle of proper diameter rotatable by a player's hand to impart a suitable motion and suitable limited velocity to said club, a miniature 'hole' to a scale substantially in proportion to the distance said ball may be projected by said club and said means, a

fuzzy playing surface forming part of said 'hole', an imitation 'water hazard' comprising a surface retentive of said ball.

23. In a miniature golf game, a light ball, a fuzzy exterior surface on said ball, a club to hit said ball, a means comprising a handle of proper diameter rotatable by a player's hand to impart a suitable motion and suitable limited velocity to said club, a miniature 'hole' to a scale substantially in proportion to the distance said ball may be projected by said club and said means, a fuzzy playing surface forming part of said 'hole', an imitation 'water hazard' comprising a suitably colored surface retentive of said ball.

24. In a miniature golf game, a light ball, a fuzzy exterior surface on said ball, a club to hit said ball, a means comprising a handle of proper diameter rotatable by a player's hand to impart a suitable motion and suitable limited velocity to said club, a miniature 'hole' to a scale substantially in proportion to the distance said ball may be projected by said club and said means, a fuzzy playing surface forming part of said 'hole', 'putting green' having a relatively smooth surface on which said ball may roll.

25. In a miniature golf game, a light ball, a fuzzy exterior surface on said ball, a club to hit said ball, a means comprising a handle of proper diameter rotatable by a player's hand to impart a suitable motion and suitable limited velocity to said club, a miniature 'hole' to a scale substantially in proportion to the distance said ball may be projected by said club and said means, a fuzzy playing surface forming part of said 'hole', a 'putting green' having a relatively smooth surface on which said ball may roll, and an inclined approach retentive of said ball.

26. In a miniature golf game, a light ball, a fuzzy exterior surface on said ball, a club to hit said ball, a means comprising a handle of proper diameter rotatable by a player's hand to impart a suitable motion and suitable limited velocity to said club, a miniature 'hole' to a scale substantially in proportion to the distance said ball may be projected by said club and said means, a fuzzy playing surface forming part of said hole, a movable 'putting green' having a relatively smooth surface on which said ball may roll and an inclined approach retentive of said ball.

In testimony whereof, I have signed my name to this specification this fifth day of January, 1922.

ARTHUR H. ADAMS.
